ELECTRON BEAM TUBE

Kern K. N. Chang, Princeton, N.J., assignor to Radio Corporation of America, a corporation of Delaware

Filed Aug. 31, 1956; Ser. No. 607,362

7 Claims. (Cl. 315—3.5)

This invention relates to electron beam tubes and in particular to improved focusing means for such tubes. While not limited thereto, the invention is herein described as embodied in a traveling wave tube.

In beam tubes it is often desirable to match two different focusing fields of the tube to each other so as to provide a smooth transition region between the two fields for the electron beam of the tube, the smooth transition region being desirable in order to minimize oscillation of electrons in their paths and to thus maintain an electron beam in substantially laminar flow. For example, it is often desirable to provide, for a traveling wave tube, an electron gun immersed in a constant magnetic focusing field, such as a field produced by a solenoid, and to immerse the delay line of the tube in a periodic magnetic focusing field spaced from the electron gun field for maintaining the beam focused in its path of travel adjacent to the line. In such an arrangement a transition magnetic is desirable between the uniform magnetic field of the electron gun region and the periodic magnetic field of the delay line region to preserve the electrons in the beam from such oscillation.

It is an object of the invention to provide an improved electron beam tube including two spaced magnetic electron beam focusing of different kinds along the path of travel of the beam, and transition magnetic field means between the fields of such character that the electrons in the beam are maintained in a smooth flow during their passage from one field to the other.

It is another object of the invention to provide an improved traveling wave tube having a substantially laminar flow of electrons through two spaced magnetic focusing fields of different kinds and wherein the electrons in the beam are maintained in substantially laminar flow through the passage thereof between the two fields.

The foregoing and related objects are realized in an electron beam tube comprising an electron gun including a cathode for projecting an electron beam along a given path, means for producing a constant magnetic electron beam focusing field that is, a unidirectional magnetic field of a given constant strength, along a first region of the path including the cathode for maintaining the beam focused along the first region, means for producing a periodic magnetic electron beam focusing field along a second region of the electron beam path spaced from the first region of the path and having a peak focusing field strength greater than the strength of the first field, and a focusing lens of adjustable field strength adjacent to adjacent ends of the two regions for providing a transition magnetic beam focusing field between the adjacent ends of the two regions.

In the drawing, where like numerals refer to like parts:

Fig. 1 is a longitudinal sectional view of a beam tube of the traveling wave type embodying the invention; and

Figs. 2 and 3 are diagrams illustrating the operation of the tube of Fig. 1.

Referring now to the drawing in greater detail, there is shown in Fig. 1 one form of traveling wave amplifier

2

tube 10 in which the invention may be used. Within an elongated envelope 12, and at one end thereof, is an electron gun 14 which may include a cathode 16 having a heater (not shown) and a plurality of accelerating electrodes 18, 20, 22, and 24 for collimating electrons, emitted from the cathode 16, to produce a beam of electrons with parallel flow along the axis of the envelope 12. The beam tube shown by way of example includes a delay line structure in the form of a helix 28 which extends axially of the envelope 12. An electron collecting element or collector electrode 30 is positioned within the envelope 12 at the end thereof remote from the electron gun 14. The collector electrode 30 and the electron gun 14 define between them the path of travel of the electron beam. In operation, a direct current power supply (not shown) would be connected to the electron gun elements 14, the helix 28, and the collector electrode 30, in order to maintain them at the desired direct current potentials with respect to each other.

A solenoid 34 around the electron gun 14 provides a constant axial magnetic focusing field along a first region of the tube including the cathode 16 and a portion of the path of the electron beam adjacent to the cathode to maintain parallel electron flow in the first region, as indicated by the linear beam path shown in Fig. 1. A periodic magnetic beam focusing structure 36 is positioned around the tube envelope 12 along a portion of the tube remote from the electron gun 14 and axially spaced from the solenoid 34. This periodic structure 36 produces a periodic second magnetic beam focusing field along a second region of the electron beam path spaced from the aforementioned first region for maintaining the electron beam focused for parallel electron flow along its path of travel adjacent to the helix 28. Preferably, the root mean square of the strength of the periodic field is substantially equal to the strength of the constant field so as to subject the electron beam in the second region (the region adjacent to the periodic structure) to a focusing field of the same average strength as that of the field in the first region (the region adjacent to the solenoid 34). The periodic magnetic structure 36 is comprised of a number of axially-spaced, axially-polarized, ring magnets 38. The magnets 38 are arranged with like poles adjacent to each other so as to produce, along the path of travel of the beam in the region of the helix, an alternating series of oppositely directed magnetic focusing fields. Ring-shaped pole pieces 40 are disposed between adjacent magnets 38 to better direct the magnetic flux of the magnets along the beam path adjacent to the helix 28. The magnets 38 are supported in the desired relation adjacent to the helix by means of a support frame 42. The input and output connections to the helix 28 are made by waveguides 44 and 46, respectively. The support frame 42 and the waveguides 44 and 46 are of any magnetically transparent metal such as copper. The portion of the periodic magnetic structure 36 adjacent to the input waveguide 44 takes the form of a ring magnet 38a having an inner diameter sufficient to extend around the portion of the waveguide 44 adjacent to the envelope 12 so that electromagnetic energy transfer between the waveguide and the helix may be effected without any substantial disturbance of the magnetic field of the periodic structure 36. The larger diameter magnet 38a has a larger cross section than that of the other magnets 30 and consequently has a stronger magnetic field which compensates for its greater distance from the helix.

According to the invention there is provided, along a region of the beam path between the constant magnetic field of the solenoid 34 and the periodic magnetic field of the magnet structure 36, a magnetic lens of adjustable field strength for providing a transition beam focusing field between the constant and periodic fields afore-

mentioned. In the form of the invention illustrated in Fig. 1, the magnetic lens of adjustable field strength takes the form of a second solenoid 50 disposed between the first solenoid 34 and the periodic magnetic structure 36. The second solenoid 50 is provided with two ring-shaped pole pieces 52 and 54 on the sides of the second solenoid 50 adjacent to, respectively, the first solenoid 34 and the periodic structure 36. This adjustable magnetic lens (the second solenoid 50 being adjustable by virtue of the fact that the field strength of the second solenoid is adjustable by varying the amount of electric current therethrough) produces an adjustable transition beam focusing field between the adjacent ends of the first and second regions, that is, between the constant magnetic field in the electron gun region of the tube and the periodic magnetic field in the helix region of the tube, for maintaining the electrons in the beam in a smooth parallel flow during their passage between the time-constant and periodic fields.

Referring now to Fig. 2, there is illustrated the configuration of the magnetic fields along the electron beam path of the tube of Fig. 1. B_o represents the magnetic field strength of the constant field in the region of the electron gun, B_L represents the peak magnetic field strength of the periodic magnetic structure in the region of the electron beam along the helix, B_L being equal to $\sqrt{2B_o}$. The dot-dash line 60 represents the magnetic field strength in the region along the beam path (Fig. 1) between solenoid 54 and the periodic structure 36.

The field configuration of the transition field lens along the tube axis is according to the following. Let the value of the axial magnetic field B_z (Fig. 2) at the two axial ends of the transition field 60 be fixed at B_o and B_L , respectively (the axial ends being O and L). Then substantially any transition field configuration will provide the smooth transition according to the invention if (Fig. 3) the integral (area A_1) of the square of the amount of the magnetic field (that is, if the integral of the amount of the magnetic force, since the square of the magnetic field is proportional to the magnetic force) less than the square of the magnetic field at $z=0$ (that is B_o^2) is equal to the integral (area A_2) of the amount of the magnetic field greater than B_o^2 . In other words, with the field strengths of the ends of the transition field fixed at B_o and $\sqrt{2B_o}$ at axial points O and L, respectively, a smooth transition between the fields at opposite axial ends of the transition field is provided when area A_1 equals area A_2 ; that is, when

$$\frac{1}{L} \int_0^L B_z^2 dz = B_o^2$$

where dz is the increment of the distance z along the tube axis. When the root mean square of the periodic field is equal to the constant field, in the example of Fig. 1, the smooth transition is a substantially laminar flow of electrons in the beam throughout substantially the entire path of travel of the electrons.

For convenience, the axial extent L of the transition field is chosen to be equal to the axial extent of one period of the periodic magnetic structure 36. However, a lesser or greater transition field axial extent may instead be used provided that the axial length L of the transition field is relatively small, that is, less than about one-fourth of the scalloping-wave-length of the beam in the constant field B_o .

For the derivation of Equation 1, reference is hereby made to my paper entitled "Periodic Magnetic Field Focusing for Low-Noise Traveling-Wave Tubes," published in RCA Review, September 1955. Equation 1 herein is the same as Equation 14 in said paper.

Using Equation 1, it is simple to design graphically any transition field by plotting B_z^2 versus z and choosing a field distribution according to Equation 1. This is shown in Fig. 3. Suppose the square of the field strength of a matching solenoid 50, which matches the constant field

B_o (Fig. 2) and a periodic field with a peak value of $B_L(2\sqrt{B_o})$, is represented by line 62. According to Equation 1 the area A_1 of the square of the field below the dashed line 64 of B_o^2 equals the area of the square of the field A_2 above the line of B_o^2 . This gives a graphic solution to the design of the field strength required of the transition lens 50.

From the foregoing it is seen that an improved electron beam tube is provided including two spaced magnetic electron beam focusing fields of different kinds along the path of travel of the beam of the tube and transition magnetic field means between the magnetic fields of such character that the electrons in the beam are maintained in a substantially smooth flow during their passage from one field to the other.

What is claimed is:

1. An electron beam tube comprising an electron gun including a cathode for projecting a parallel flow electron beam along a given path, means for producing a constant first magnetic focusing field of a given strength along a first region of said path including said cathode, means for producing a periodic magnetic second beam focusing field along a second region of said path spaced from said first region and having a peak strength at the end of said second region nearest to said first region substantially greater than said given strength of said first magnetic field, and magnetic field producing means, separate from said first and second named means, for producing a transition magnetic beam focusing field along a third region extending between the adjacent ends of said spaced regions.
2. An electron beam tube according to claim 1 wherein said means for producing said first magnetic field comprises a solenoid.
3. An electron beam tube according to claim 1 wherein the magnetic field strength of said first magnetic field is substantially equal to the root mean square of the peak value of the field strength of said periodic second magnetic field.
4. A traveling wave tube comprising means including a cathode for projecting a parallel flow electron beam along a given path, an elongated signal wave propagating structure disposed adjacent to said path and adapted to propagate a traveling signal wave along said structure, means for producing a constant magnetic beam focusing field of a given strength along a first region of said path including said cathode for maintaining said beam at a predetermined transverse extent along said first region, means for producing a periodic magnetic beam focusing field along a second region of said path spaced from said first region and including said structure having a peak magnetic field strength at the end of said second region nearest to said first region substantially greater than said given strength of said first magnetic field, and a solenoid of adjustable field strength effective in a third region extending between said spaced first and second regions for producing a transition electron beam focusing magnetic field therebetween.

5. A traveling wave tube according to claim 4, wherein 60 said means for producing said focusing field along said first region comprises a solenoid; and wherein the magnetic field strength of said beam focusing means of said first region is substantially equal to the root mean square of the peak value of the field strength of said periodic focusing field.

6. An electron beam tube comprising means including a cathode for projecting an electron beam along a given path; means for producing a constant first magnetic beam focusing field of a given strength B_o along a first region of said path including said cathode for maintaining said beam focused along said first region; means for producing a periodic second magnetic beam focusing field along a second region of said path spaced by a distance L along the path from said first region and having a peak field strength B_L at the end of said second region nearest to

said first region substantially equal to $\sqrt{2}$ times the field strength B_o of said first region adjacent to said second region; and separate means for producing a transition magnetic beam focusing field of adjustable field strength between the adjacent ends of said spaced regions; the field strength of said transition focusing field at the portion thereof adjacent to said end of said first region being substantially B_o , the field strength of said transition field at the portion thereof adjacent to said end of said second region being substantially B_L , and

$$\frac{1}{L} \int_0^L B_z^2 dz = B_o^2$$

where dz is the increment of the distance along said beam path, and B_z is the strength of said transition field at any given point along said beam path between said adjacent ends of said first and second regions.

7. An electron beam tube according to claim 3, where-
in

$$\frac{1}{L} \int_0^L B_z^2 dz = B_o^2$$

where L is the distance between said first and second

5

6

regions, dz is the increment of the distance z along the beam path between $z=0$ and $z=L$, B_z is the strength of the transition magnetic field at any distance z and B_o is the given strength of the first magnetic field.
